UNITED STATES PATENT OFFICE.

JOHN JAMES HAMPSON AND JOHN WILLIAM KELSALL, OF MANCHESTER, ENGLAND.

MACHINE FOR FILLING AND LOADING FABRICS.

Application filed November 17, 1924. Serial No. 750,501.

To all whom it may concern:

Be it known that we, JOHN JAMES HAMPSON and JOHN WILLIAM KELSALL, both subjects of the King of Great Britain, residing in Manchester, England, have jointly invented certain new and useful Improvements in Machines for Filling and Loading Fabrics, of which the following is a specification.

This invention relates to machines for carrying out filling, loading and analogous operations on continuous lengths of fabrics, the machines being of a known kind which comprises a vertically adjustable top bowl or roll driven from a main driving shaft, a pair of relatively adjustable horizontal bottom bowls arranged tandemwise and in a manner to be driven from the said shaft in either direction of rotation and so as to convey liquid filling or loading substance from a source of supply or liquor box on the machine and apply it to fabric passing over suitable tensioning devices, and also a number of yieldingly mounted doctor knives, the bowls and doctors being adjustable in position to permit of the degree or extent to which a fabric is to be loaded being varied.

The invention consists in improved construction and arrangement of parts as hereinafter described and claimed.

The machine is provided with a pair of starch or other liquor-containing tanks or boxes, which make it possible to charge the machine with two different substances, and allow of additional impregnating or coating processes, as enumerated below, to be carried out simultaneously on one and the same machine. These boxes, preferably constructed with wooden bottom and iron sides, are mounted in a manner to allow them to be tilted for cleaning and other purposes, and are associated with means whereby they can be rocked or tilted. A roller is provided for guiding the fabric during some processes from one box into the other.

By providing a machine with two liquid containing boxes, the following additional stiffening and filling processes, besides others not illustrated, can be carried out, viz: double frictioning, single frictioning, frictioning and stiffening, and back filling with back skimming.

In order to ensure that there shall be no seizing of the lower bowls owing to the adjustably slideable bearings supporting the bowl spindles becoming out of truth, the bearings, instead of being mounted directly

as heretofore on the main frame of the machine, are carried by auxiliary bed plates or frames that are bolted or otherwise conveniently fixed to the main frame.

Means are provided whereby, while the top bowl turns, one or both of the lower bowls can be made to remain stationary or revolve, and the gears for driving these bowls are so designed that these bowls can, if desired, be run faster than the upper bowl for friction or Scotch mangling, starch being applied to the fabric by friction motion.

Another improvement consists in means correlated with the bottom bowls for controlling the thickness of the film of starch applied to the cloth and is so arranged that it can be adjusted for either forward or reverse motions as may be necessary in the following processes, double back skimming, single back skimming, back filling, and back filling with back skimming.

A further improvement is that the gear wheel, which is fixed to the shaft carrying the upper bowl and is used to rotate the shaft and bowl, is driven, during operations requiring its rotation, directly from a gear wheel keyed to the main driving shaft, instead of indirectly by the latter gear wheel through one or more intermediate gears, as previously proposed.

One of the main objects of the invention is to produce a machine of the kind referred to which is more compact than has been hitherto the case, which affords an operator or attendant easier access to the parts that need adjustment from time to time and wherein there may be a nearer supervision of the work than what has been customary.

To these ends, the lower bowls and doctors, the tensioning devices and other elements are placed, as compared with known machines, in positions nearer the vertical plane containing the axis of the upper or squeezing bowl.

The invention will be described with reference to the accompanying drawings, in which:

Fig. 1 is a side elevation of a filling or loading machine of the kind referred to above and embodying the improved construction and arrangements, some parts being omitted or broken away.

Fig. 2 is a detail sectional drawing showing a doctor knife and its holder arranged between the pair of lower bowls as indicated in Fig. 1.

Fig. 3 is a broken fragmentary sectional plan view of some parts shown in Fig. 1, the section being taken through the upright frame which supports the spindle of the 5 top bowl.

Figs. 4-14 are diagrams, to a reduced scale, showing the top and bottom bowls of the machine in Fig. 1 variously arranged for carrying out the different processes mentioned herein, and Fig. 15 is a diagrammatic view showing the travel of a length of fabric through the machine from the inlet to the outlet thereof during a frictioning and stiffening operation.

15 In the drawings the reference numeral 1 denotes the top bowl or roll, and 2 and 3 are the bottom bowls or rolls. The top bowl 1 is carried by a transverse shaft 4 supported in bearings, one of which is 20 shown at 5 slidably mounted in an upright frame 6, which may be, as shown in Figs. 3, of channel section and is fixed to a main base frame 7. The bearings 5 are vertically adjustable in upright guides 8 by 25 means of a pair of screw-threaded rods which are arranged one on either side of the machine, one being shown at 9 in Fig. 1. Each of the rods 9 co-operate with a screw-threaded nut device formed in a boss 10 on 30 a lever 11 pivoted at one end 12 on supports 13 on the guide frame 6. The rods 9 are each adapted to be turned by means of hand-wheels 9'. The other ends of the two levers 11 are, as in known machines, each connected to one end of a link 14, which may be 35 adjustable in length and is at its other end pivotally attached to a lever 15 which is pivoted at its end 16 to a part of the frame 7, and at its other end carries an adjustable 40 weight 17. The top bowl 1 is thus suspended and, when it meets with any undue pressure, rises and yields to such pressure and return to its normal position when that pressure ceases.

45 The bearings 5 may each carry a pointer 18 which, as the bearings are raised or lowered, passes over graduated markings 19 on the frame 6 thereby enabling the bearings to be accurately adjusted to the same 50 level.

Means, such as blocks 30 adjusted by studs 30', screwable in position on the upright frame 6 may be provided for limiting the movement of the bearings 5 in a 55 downward direction.

The bottom rolls 2 and 3 are horizontally adjustable towards and from one another, and are carried by transverse spindles 20 and 20'. Spindle 20 is supported in two 60 terminal bearing blocks 21 mounted one on each side of the machine. Each of the blocks 21 is adapted to be moved along a horizontal guideway 22 between guides 23, which are mounted on a suitably constructed auxiliary bed plate or frame 24 secured

in any appropriate manner to the main base frame 7.

Connected with each block 21 is a screw-threaded rod 25 that co-operates with screw-threads formed in nut fashion in the bored hub of a bevel wheel 26 that meshes with a similar bevel wheel 27 carried by a spindle 28 suitably supported on a part of the machine framing. By turning the spindle 28 by means of a hand-wheel 29, or in any other convenient way, the block 21 can be moved along the guideway 22 in one direction or the other as may be required.

The spindle 20' carrying roll 3 is supported in terminal bearing blocks 21' which are adapted to be moved, in a similar manner to blocks 21, along a guideway 22' between guides 23' on the frame 24', by means of the screw-threaded rod 25' co-operating with nut threads on the bevel wheel 26' in 85 mesh with bevel wheel 27' on spindle 28' that can be turned by means of hand-wheel 29'.

By adjusting the bearings of the spindles of bowls 1, 2 and 3 in position as described above, either one or two nipping points may be arranged between the curved surface of the bowls or alternatively the three bowls may be entirely separated.

The top bowl 1 is driven from the main driving shaft 31 which carries a toothed wheel 32 with which a toothed wheel 32' keyed to the shaft 4 of the bowl 1 can be moved into and out of direct engagement by operating the hand-wheel 9'.

The lower rolls 2 and 3 are also driven from the main driving shaft 31 by means of mechanism which permits of one or both rolls being turned at one and the same time, and in either direction. The mechanism comprises a pair of bevel wheels 33 loose on the shaft 31 and in mesh respectively, at diametrically opposite points, with a bevel wheel 34 on the lower end of a vertical shaft 35 mounted in suitable bearings on the frame 7, and it also includes a clutch device 36 mounted to rotate with shaft 31 and to slide along a feather thereon. The clutch is operated by means of a two-arm forked appliance 37 which is keyed to a spindle 38 carried by supports 39, the arms being yoked to the clutch. The spindle and clutch are controlled by means of a hand lever 40 which is located at the front of the machine and is moved in one direction or the other so that the device 36 clutches one or other of the bevel wheels 33 according to the direction in which shaft 35 is to be turned.

The upper end of shaft 35 carries a bevel wheel 41 which gears with a bevel wheel 42 fixed to a shaft 43 supported at its ends in bearings 44 carried by the frame 7. On extensions 20* to the spindles 20 and 20' of the lower bowls 2 and 3 are, respectively, keyed bevel wheels 130

45 and 45', and slidably mounted on shaft 43 are two bevel wheels 46 and 46' which, by means of mechanisms described below, can be individually moved into and out of engagement with wheels 45 and 45' respectively. Each of said mechanisms comprises a pair of pins 47 slidably mounted on a supporting block 48 carried by the shaft 43, by means of a pivoted bearing inside 10 of the respective supporting block 48, and by the extended portion 20* of shaft 20 or 20' as the case may be, traversed by the shaft 43. Each pin has a finger 49 that projects into a grooved hub 50 or 50' on 15 wheel 46 or 46'. Each pair of pins 47 can be slid to and fro by means of yoke pieces 51, slidably mounted on blocks 48 and coupled each to an operating handle 52 pivoted at 52' on the corresponding block 48. By 20 turning the proper handle 52 on its pivot the wheel 46 or 46' can be made to engage with or be disengaged from wheel 45 or 45' respectively. The ends of the extended portions 20* of the shafts 20 and 20' are 25 housed in the adjacent blocks 48 so that when the bearing 21 or 21' is adjusted in position by being moved lengthwise of the guideways 22 or 22', the corresponding block 48 and parts associated with it will 30 have a corresponding movement.

The machine as illustrated is provided with two liquor-containing boxes or tanks 53 and 54, one for each bottom bowl. Means are preferably provided for rocking or tilting 35 these tanks which at their inner ends may be pivoted or hinged together as indicated at 55, or in other convenient way. The means for rocking the tanks may consist in eccentrics 56 rotatably mounted in 40 suitable bearings on the frame 7 in a position wherein they bear upon the under faces of the bottoms of the tanks. The eccentrics may be turned in their bearings by means of the handles 56'. Each tank may be provided, as is customary, with one or more 45 power driven agitators. In the machine illustrated one such agitator is indicated in each tank at 57.

A doctor knife 58 is, as is customary in 50 machines of the kind referred to, provided to operate as required between the bottom bowls 2 and 3. The knife 58 and its holder 59, Fig. 2, is detachably fixed in any convenient manner in a sector-like member 60 55 that is arranged to turn about a pivot or spindle 61 on a block 62 arranged one on each side of the machine. Each block is connected with a rod 63 by which it can be made to slide up and down a bracket 64 in known manner, for the purpose of making the knife approach or recede from the cylindrical surface of the top bowl 1. The means for rocking the member 60 60 with the knife 58 about the pivot 61, so as to vary the knife's inclination to and

pressure on the fabric being loaded or treated, comprise, according to the present invention, a link 65 which is provided at one end with an appropriately shaped nose 66 that is arranged to engage in one of two 70 recesses 67, 68 in the sector 60 according to the angle of inclination at which the knife is held. When the required pressure of the knife on the fabric is light, the link 65 may be fixed in various adjusted positions, for 75 which purpose the end of the link remote from the knife is slotted by which it can be secured by means of a pin 69 at varying heights in a slotted bracket 70 supported from the machine frame, the height of the 80 pin connection determining the inclination of the knife 58 to the roll surface. Preferably, two links 65, one on each side of the machine, would be provided.

If the required pressure of the knife 58 85 on the fabric is heavy, the link would not have its outer end fixed or pinned as just described, but would be free to move and there would be suspended from the link 65 a suitable weight 71 which would tend to 90 turn the sector 60 and knife 58 about the pivot 61 so as to cause the knife to impart pressure against the fabric when the knife is in operation.

A second doctor knife 72 may be provided 95 in rear of or at the exit side of the bowl 3. This knife is adjustable in position for the purpose of varying the pressure exerted by it on the fabric being treated or of moving it clear of the same. The knife is, in known manner, attached to a holder 73 carried by a spindle 74 journalled in blocks 75 slidably mounted in upright frames 76 secured to the main frame 7, one on each side of the machine. The blocks 75 can be raised and lowered by means of the screwed rods 77 and hand wheels 78, and their inclination to the vertical can be adjusted by means of the member 79 that co-operates with the holder 73. 100

Associated with the upper bowl 1 there may be a cleaning knife 80 which can be of rubber and be held in a holder 81 carried by a rocking spindle 82 mounted on a block 83 that is adjustable in position by means of a device 84 in a guideway provided on a bracket 85 fixed to the upright frame 6. Supported by the spindle 82 is a lever or bar 86 that carries a weight 87 that can be adjusted in position along the bar 86 105 to vary the pressure exerted by the knife 80 against bowl 1. 115

The device provided for controlling the thickness of the film of starch or other substance applied to the cloth or other material being loaded, comprises a roller 88 of which the shaft is removably and loosely journalled in arcuate grooves 89 formed in bracket members 90 fixed to the machine frame 6, one on each side thereof. The arcu- 120 125 130

ate grooves 89 of the bracket members 90 are concentric with the axis of rotation of the bowl with which the roller 88 cooperates. Thus the brackets and the arcuate grooves 5 thereof are so disposed that the roller, when supported by the brackets extends lengthwise above the bowl with which it co-operates. The roller, when in use, is arranged to occupy one of two operative positions, 10 such positions being at the two ends of the arcuate grooves 89. It would occupy one of those positions when the adjacent bottom bowl is to turn in one direction, and it would occupy the other position when the 15 bowl is to rotate in the reverse position. The journals 91 of the roller can be introduced to and removed from the grooves 89 by passing them through the openings or gaps 92 provided in the walls of the grooves. 20 Such a starch film controlling device may be associated with each of the bowls 2 and 3.

The cloth fabric or other material to be loaded enters the machine over tensioning 25 rails 93 which are carried by longitudinal members 94 supported by brackets 95 fixed to the frame or frames 6, and in certain loading processes, for instance in double stiffening (Fig. 4) also about rails 93' on 30 brackets 100 carried by the frames 24. From the tension rails the material passes about two horizontal bars 96, 97 carried by a frame or part 98 which has journals 99 that engage in bearings provided in the 35 brackets 100. The frame 98 is shown in Fig. 1 in a vertical position, but it can be placed at any desired inclination for tensioning purposes by turning it in its bearings and fixing it in adjusted positions by 40 means of a pin 101 that passes through a hole in the bracket 100 and projects into one or other of the holes in the circular row 102 on the frame 98.

For the purpose of guiding the fabric 45 during some of the above-mentioned processes from one of the two tanks to the other, a roller 103 is suitably mounted on the machine framing.

As is usual, a guide roller 104 is provided 50 on the exit side of the machine. The roller is carried by two bearing blocks 105, one on each side of the machine, the blocks being slidably mounted in a bracket 106 supported from the frame 7. The blocks can be raised 55 and lowered by means of the screwed rod 107 which can be turned by actuating bevel gears 108 controlled by hand wheel 109. Attached to a spindle 110 carried by a bearing block 110' supported on the member 94 is 60 a draw roller 111 driven by a belt 112 from main driving shaft 31.

As stated above, the diagrams, Figs. 4-14, show the top and bottom bowls 1, 2 and 3 variously arranged for effecting various 65 processes.

The arrangement in Fig. 4 is for double stiffening.

The arrangement in Fig. 5 is for single stiffening.

The arrangement in Fig. 6 is for single 7 friction.

The arrangement in Fig. 7 is for double friction.

The arrangement in Fig. 8 is for friction and stiffening.

The arrangement in Fig. 9 is for single padding.

The arrangement in Fig. 10 is for double padding.

The arrangement in Fig. 11 is for single 80 back skimming.

The arrangement in Fig. 12 is for double back skimming.

The arrangement in Fig. 13 is for back filling.

The arrangement in Fig. 14 is for back filling and back skimming.

Fig. 15 shows diagrammatically the travel of a piece of fabric or other material 113 through the machine during a friction and 90 stiffening process. The materials supplied from a wagon or batch (not shown), as the case may be, enters the machine over the first tensioning rails 93 and about the other rails 93'. From the last of these rails 95 it passes downwardly about the bars 97 and 96 and the rails 93', between bowls 1 and 2 and between bowls 1 and 3. Issuing from between bowls 1 and 3, the material passes upwardly to the draw roller 111 160 around which it travels on its way to plaiting or batching mechanism which is not shown.

Having thus described the nature of the 105 said invention and the best means we know of carrying the same into practical effect, we claim:—

1. In a machine for filling and loading a continuous length of fabric, a pair of bottom bowls over which said length of fabric travels, means for rotating said bowls in either direction, a pair of liquor-containing tanks associated, respectively, with said bottom bowls, and means for controlling the thickness of the liquid film applied 110 to said length of fabric by one of said bowls, said means comprising a member adapted to bear against said length of fabric and said bowl and shiftable, according to the direction of rotation of said bowl, from one side to the other of a vertical plane passing through the axis of rotation of said bowl.

2. In a machine for filling and loading a continuous length of fabric, a pair of bottom bowls over which said length of fabric travels, means for rotating said bowls in either direction, a pair of liquor-containing tanks associated, respectively, with said bottom bowls, and means for control- 125 130

- ling the thickness of liquid film applied to the fabric by one of said bowls, said means comprising a roller bearing against said bowl and between which and said bowl the 5 strip of fabric passes, a member mounted above each of the opposite ends of said bowl and having an arcuate slot concentric with the axis of rotation of said bowl and extending to points on opposite sides of a vertical plane passing through the axis of rotation of said bowl, and a shaft for said roller having its ends mounted in the slots of said members and shiftable from one end to the other of said slots according to the 10 direction of rotation of said bowl.
3. Apparatus according to claim 2 wherein one of the members having the arcuate slots has a gap opening into its slot through which one end of the shaft of the roller may 15 be introduced into and removed from said slot.
4. In a machine of the character described for filling and loading a continuous length of fabric, the combination of a main frame, 20 a main driving shaft mounted thereon, a vertically adjustable rotatably mounted shaft, a top bowl fixed to said shaft, a pair 25 of relatively adjustable rotatably mounted spindles, a pair of bottom bowls carried respectively by said spindles and driven from the main driving shaft, a gear on the main driving shaft, a gear carried by the first said shaft, and means for moving the latter gear into and out of direct engagement with the former gear. 30
5. In a machine of the character described for filling and loading a continuous length of fabric, the combination of a main frame, a main driving shaft mounted thereon, a vertically adjustable rotatably mounted shaft, a top bowl fixed to said shaft, auxiliary frames detachably connected to the main frame, a pair of relatively adjustable rotatably mounted spindles carried by said auxiliary frames, a pair of bottom bowls carried respectively by said spindles and driven from said main driving shaft, a gear on said main driving shaft, a gear carried by the first said shaft, and means for moving the latter gear into and out of direct engagement with the former gear. 35 40 45 50

In testimony whereof we have signed our names to this specification.

JOHN JAMES HAMPSON.
JOHN WILLIAM KELSALL.
